UNITED STATES PATENT OFFICE.

ERNEST E. GAMON, OF NEWARK, NEW JERSEY.

WATER-METER.

961,116.

Specification of Letters Patent. Patented June 14, 1910.

Application filed May 18, 1909. Serial No. 496,852.

To all whom it may concern:

Be it known that I, ERNEST E. GAMON, a citizen of the United States, residing in the city of Newark, in the county of Essex and 5 State of New Jersey, have invented certain new and useful Improvements in Water-Meters, of which the following is a full, clear, and exact description, such as will enable others skilled in the art to which it 10 pertains to make and use the same.

My invention relates to water meters of the disk type, comprising an outer inclosing case and an inner piston chamber in axial alinement with the inclosing case and 15 circumferentially free therefrom, the disk chamber being provided with suitable inlet and outlet ports and containing the nutating piston or disk.

The inlet and outlet ports of the disk 20 chamber communicate with inlet and outlet ports or spuds in the outer inclosing case, the spuds being connected to the water pipes in the usual way.

The object of my invention is to simplify 25 and cheapen the construction by attaching the disk chamber in a simple manner to an annular boss in the bottom of the inclosing case, and having the outlet port of the disk chamber communicating through the annular 30 boss with the outlet spud. It will be seen that this construction permits a free circulation of the water about the disk chamber thus equalizing the pressure and breaking up the current before it enters the disk 35 chamber. Furthermore, the simple screw-attachment reduces the amount of machining and fitting necessary and facilitates assembling the parts.

In carrying out my invention, I make use 40 of the construction illustrated in the accompanying drawings, in which—

Figure 1 shows a vertical elevation, the lower part being broken away and shown in section. Fig. 2 is a plan view; and Fig. 3 45 shows a modification.

Similar letters of reference refer to like parts throughout the specification and drawings.

The inclosing case is composed of two 50 shell-like castings A and B fastened together in any suitable manner as by bolts C. The upper casting A has the register inclosing compartment D cast on or otherwise secured

thereto, and is provided with the usual cover E.

The registering mechanism and gear train 55 may be of the usual type in common use in meters, hence they are not here shown.

The lower casting B is practically hemispherical in shape and is provided with an 60 inlet spud F and an outlet spud G integral therewith; the inlet spud F being continuous with the tubular channel F' extending downward as a rib on the exterior of the inclosing case B and opening into the interior of 65 the inclosing case B near the bottom thereof, as shown in Fig. 1.

An annular boss H rises from the bottom 70 of the casting B and is in direct communication with the outlet spud G through the tubular channel G' which extends rib-like along the exterior of the case B, diametrically opposite the inlet tube F', as clearly 75 shown in Fig. 1. The boss H is internally threaded at I and surfaced off to form the seat K upon which the disk chamber L, L' is secured by the depending stem M which is provided with the tubular threaded boss N, taking into the threads I of the boss H. The under face of the stem M is surfaced off to 80 coact with the seat K to form a water tight joint.

In a water meter, the water is usually caused to flow through the disk chamber in a counter-clockwise direction, in which case, 85 the threads I may be made left-handed so that the frictional action of the flowing water in the disk chamber will tend to maintain a tight joint at K, although I have used a right-hand thread with satisfactory results.

It will be seen that the disk chamber L, L' is spaced away from the inclosing case A, B, thereby forming a receiving chamber for the inflowing water from the spud F. The disk 95 chamber is made up of two sections L and L', secured together in any suitable manner, as by screws L², and provided with inlet and outlet ports. The inlet port is similar to that in common use in meters of this type, 100 and opens directly into the receiving chamber above mentioned, while the outlet port opens into a pocket R cast integral with the sections of the disk chamber and is continuous and integral with a tubular cavity S 105 cored in the stem M, depending from and in-

tegral with the lower section L of the disk chamber. A supplemental port R' is added to give more free egress of the water from the disk chamber to the channel S. The 5 outlet port of the disk chamber is thus connected to the outlet spud G by a sinuous tubular channel which leads through the central boss H.

It will be seen that in manufacturing, all 10 the fitting necessary will be at the seat K, and this can be quickly and cheaply done by facing off the upper face of the annular boss H and the lower face of the stem M and cutting the threads.

15 Near the bottom of the lower section B of the inclosing case, is placed a strainer T of perforated metal. It is made annular in shape to fit over the boss H and may be held in place in any desired manner, as by the 20 overhanging edge of the depending disk chamber stem M. The cavity thus formed below the strainer T serves as a receptacle for gravel and other particles separated from the inflowing water by the strainer T.

25 The disk chamber is provided with the usual nutating piston U having a ball bearing V and gear train actuating rod W, which being of usual construction, require no special description here.

30 In carrying out my invention, the disk chamber may be attached to the bottom of the inclosing case in various ways. In Fig. 3 is shown a modification in which a larger annular boss H³ is employed to support the 35 disk chamber L³ which is provided with a corresponding depending annular boss M³. The surfaces of the bosses H³ and M³ are faced off to form the water tight seat at K³. An additional central boss H⁴ is provided 40 and internally threaded to receive a central lug or bolt M⁴ depending from the under side of the disk chamber L³. The outlet port of the disk chamber communicates by an integral pocket R³ with the annular cavity S³, 45 the latter communicating with the outlet spud G³ which is cast with the inclosing case B³. The inlet spud F³ communicates with the receiving chamber formed between the disk chamber and the outer inclosing case, as 50 in the previously described construction.

The operation of my improved meter should be sufficiently clear from the description and an inspection of the drawings.

The flow of the water may be traced by 55 following the arrows from the inlet spud F through the tubular channel F' and up through the strainer T to the receiving chamber about the disk chamber L, L', then through the disk chamber and out through 60 the ports R, R' down through the channel S and the boss H up through the tubular channel G' and out through the spud G.

I claim:

1. A water meter comprising an inclosing

case provided with inlet and outlet spuds, 65 an annular boss integral with one of said spuds, a disk chamber provided with inlet and outlet ports located within and circumferentially free from said inclosing case and separated therefrom to form a receiving 70 chamber and a central tubular stem depending from said disk chamber and registering with said annular boss.

2. A water meter comprising an inclosing case provided with inlet and outlet spuds, 75 an annular boss integral with said outlet spud and a disk chamber provided with a central depending stem having a continuous tubular channel therein registering with said boss, said disk chamber provided with inlet 80 and outlet ports and being axially located within said inclosing case and separated therefrom to form a receiving chamber, said inlet port communicating with said receiving chamber and said outlet port communicating with said outlet spud by the annular boss and continuous tubular channel through 85 said central stem.

3. A water meter comprising an inclosing case, and a disk chamber circumferentially 90 free from said inclosing case, provided with a central depending stem having a tubular boss extending therefrom said stem and boss having a continuous tubular channel therein and serving as means for securing said 95 chamber in axial alinement to said inclosing case.

4. A water meter comprising an inclosing case, and a disk chamber circumferentially 100 free from said inclosing case, provided with a central depending stem, a threaded boss integral with and extending therefrom said boss and stem provided with a continuous tubular channel therethrough.

5. A water meter comprising an inclosing 105 case provided with an interiorly located integral annular boss on the bottom thereof, and a disk chamber circumferentially free from said inclosing case, provided with a central depending stem having a continuous 110 tubular channel therein said stem coacting with said annular boss for securing said disk chamber to said inclosing case.

6. A water meter comprising an inclosing case, provided with inlet and outlet spuds 115 extending downwardly as ribs on the exterior and opening into the inclosing case near the bottom thereof, an annular boss integral with said outlet spud, and a disk chamber circumferentially free from said 120 inclosing case provided with a central depending stem having a continuous tubular channel therein said stem coacting with said annular boss for securing said disk chamber to said inclosing case.

7. A water meter comprising an inclosing case, securing means in said case and a disk chamber, circumferentially free from said

inclosing case provided with central depending means having a continuous tubular channel therein said depending means coacting with said securing means for securing said

5 chamber to said inclosing case.

8. A water meter comprising an inclosing case, securing means in the bottom of said case, a disk chamber circumferentially free from said inclosing chamber and provided

10 with central depending means having a con-

tinuous channel therein said depending means coacting with said securing means for securing said chamber to said inclosing case.

This specification signed and witnessed 15 this 10th day of May, 1909.

ERNEST E. GAMON.
